UNITED STATES PATENT OFFICE

ALFRED BOUSFIELD, OF ST. JOHNSBURY, VERMONT

DESIGN FOR A HEALTH SCALE

Application filed November 11, 1932. Serial No. 45,889. Term of patent 14 years.

To all whom it may concern:

Be it known that I, ALFRED BOUSFIELD, a citizen of the United States, residing at St. Johnsbury, in the county of Caledonia and State of Vermont, have invented a new, original, and ornamental Design for a Health Scale, of which the following is a specification, reference being had to the accompanying drawing, forming part thereof.

In the drawing:

Figure 1 is a perspective view of a scale showing my new design; and

Figure 2 is a side view of the scale.

I claim:

The ornamental design for a health scale, as shown.

ALFRED BOUSFIELD.
